UNITED STATES PATENT OFFICE.

GEORGE P. BRAND, OF NEW YORK, N. Y.

TRACKER DEVICE.

1,014,942.

Specification of Letters Patent.

Patented Jan. 16, 1912.

Application filed May 10, 1910. Serial No. 560,410.

To all whom it may concern:

Be it known that I, GEORGE P. BRAND, a citizen of the United States of America, and resident of New York, in the county of 5 New York and State of New York, have invented certain new and useful Improvements in Tracker Devices, of which the following is a specification.

This invention relates to certain new and 10 useful improvements in tracker bars for self-playing or automatic musical instruments and it has for its objects among others to provide a simplified construction whereby one part is made movable to 15 change the position of the bleeds in accordance with the desire to adapt the player for playing sixty-five or eighty-eight note music.

In the present sixty-five note player that 20 is built for sixty-five note music only, the holes in the music are of a certain diameter and the bridges between the perforations of the paper very often are made so small that it is necessary to use very large bleeds to 25 obtain the proper repetition as the bridges are just long enough to barely cover the holes or ducts in the tracker bar. Therefore, the bleeds have to be made sufficiently large to return the valve mechanism in time 30 to strike another note for the following perforation.

In the eighty-eight note player that is built exclusively for eighty-eight note music, the perforations in the music are 35 much smaller and as they run at about the same speed as the music of the sixty-five note, there is always more bridge left between the perforations than there is in the sixty-five note music. Consequently, I can 40 use smaller bleeds. In fact, I have to use smaller bleeds as there is not sufficient air allowed to enter the tracker bar in the eighty-eight note music to allow the bleeds to be of the same size as for the sixty-five 45 note music. As is well-known, tracker bars have been devised for adapting the player for use in connection with sixty-five or eighty-eight note music. Such tracker bars are provided with two series of ducts one 50 larger than the other, those for playing sixty-five note music being larger and disposed six to the inch, while those for eighty-eight note music are smaller and formed nine to the inch. Now, if I employ in the 55 player that is built to play both sixty-five and eighty-eight note music, two sets of

bleeds of different sizes, the set of smaller bleeds for the eighty-eight note ducts in the tracker, and the set of larger bleeds for the sixty-five note ducts in the tracker, there being as many bleeds in each set as there are ducts in each set in the tracker bar, it is necessary to have means to cut off one set while using the other and vice versa, thereby giving the action the same result as 60 would be obtained in two different players. Unless some means is provided to throw out of action the set of bleeds for the one series of openings as the other set of bleeds is thrown in, there is a loss of energy. By my 65 improvement, I make movable a single part so that as said part is moved, the bleeds of one or the other of the series of ducts in the tracker bar are thrown into and the other out of, operative relation to the series of 70 ducts with which they are designed to co-operate. For instance, if the player is arranged for playing sixty-five note music, the sixty-five note bleeds will be in communication with the sixty-five note series of 75 ducts in the tracker bar and also with the action and the bleeds for the eighty-eight note music will be out of register with the ducts in the tracker bar adapted for playing eighty-eight note music. When it is 80 desired to adapt the player for use in connection with eighty-five note music, said movable part is actuated to throw the eighty-eight note bleeds into register with the ducts of the tracker bar adapted for 85 playing eighty-eight note music and simultaneously therewith the bleeds adapted for co-operation with the sixty-five note ducts of the tracker bar are thrown out of register with the ducts of the tracker bar which are 90 designed for playing such sixty-five note music.

Simple means are provided for moving the movable part, said means being readily accessible from the front of the player, said 95 movable part being adapted to be held in its adjusted position by friction or otherwise and suitable means are also provided for limiting the movement of said parts and serving also to hold it against undue lateral 100 movement.

Other objects and advantages of the invention will hereinafter appear and the novel features thereof will be particularly pointed out in the appended claims.

The invention is clearly illustrated in the accompanying drawings, which, with the

numerals of reference marked thereon, form a part of this specification, and in which—

Figure 1 is a top plan with portions broken in two. Fig. 2 is a vertical section as on the line 2—2 of Fig. 1 with portions broken away, showing the parts in position for playing eighty-eight note music. Fig. 3 is a similar view showing the position of the parts changed and adapting the same for use in connection with sixty-five note music. Fig. 4 is a detail in vertical section on the line 4—4 of Fig. 1. Fig. 5 is a face view of a portion of the tracker bar showing the two series of ducts therein.

15 Like numerals of reference indicate like parts throughout the several views.

Referring to the drawings, 1 designates the tracker face, over which the music sheet passes. It is provided with one series of 20 ducts 2, eighty-eight in number, nine to the inch for eighty-eight note music, and another row of holes or ducts 3, sixty-five in number, six to the inch, for sixty-five note music. It is to be understood, however, that 25 the invention now to be described is as applicable to any form of tracker bar having two series of ducts of different size or differently spaced whether adapted for music of sixty-five or eighty-eight notes, or any 30 other different characters of music.

4 is a valve member provided with a chamber having suitable provision, as the tube 5, for connection with the ordinary pneumatic action of a pneumatic musical instrument.

6 are pipes or conduits, flexible or otherwise, connected at one end with the tracker face 1 for communication with the ducts 2 and at the other end communicating with 40 the short tubes or the like 7 supported in opposite walls of the chamber 4, as seen clearly in Figs. 2 and 3. By this means, all direct communication between the tubes 6 and the interior of the chamber 4 is cut off.

45 8 are a series of tubes having one end in communication with the ducts 3 of the tracker face and the other ends suitably connected with the short tubes 9 supported in the opposite walls of the chamber 4, so that 50 direct communication between said tubes 8 and the interior of the chamber 4 is cut off. It is evident, however, that any other suitable means of connection between the tubes 6 and 8 and the chamber 4 may be employed.

55 10 is a bar parallel with the chamber 4 and having suitable means, as tubes or pipes 11, designed for connection with the sound producing devices of the player, of usual construction. This bar 10 has a series 60 of ducts, one for each tube 11, and leading from each duct 12 are two openings 13 and 14 properly spaced apart, as seen in Figs. 2 and 3.

55 15 is a bleed hole for the duct 2 and 16 is a larger bleed hole for the duct 3. There is

a bleed hole for each duct 2, and a bleed hole for each duct 3. These bleed holes are relatively spaced apart and spaced relatively also to the ports or openings 13 and 14, so that when, say for instance, the 70 ports 13 are in communication with the bleeds 16, the bleeds 15 are closed from communication with the ducts 12, the openings 14 at this time being in communication with the tubes 8. When the parts are relatively moved so that the ducts 13 are in communication with the tubes 6, the bleeds 16 are shut off or closed and the bleeds 15 are in communication with the ducts 12 through the port 14. Figs. 2 and 3 show the parts 80 in these two positions.

Suitable means may be provided for moving either the chamber 4 or the bar 10 with relation to each other. In the present instance I have shown a lever 17, one end 18 of 85 which is arranged in position free of access from the front of the player, its other end being fulcrumed at 19 on a suitable standard or support 20 soldered or otherwise fastened to the tension chamber 4. This lever has 90 pivotally connected therewith, as at 21, a link or the like 22 pivotally mounted, as at 23, on a lug or projection 24 on the bar 10. The rod or pivot 19 extends through from side to side and at the end opposite said 95 lever is mounted in an arm 25 from which depends a link 26, set screws or the like 27 being provided at opposite ends, as seen clearly in Fig. 1, to insure proper movement of the rod by actuation of the lever 100 without any tendency to be strained or distorted and to insure the relative movement at the two ends of the two members 4 and 10. It is to be understood that there are as many ducts and tubes in the bar 10 (adapted to be connected with the action) as there are in the row of the tracker bar having the greatest number, and there are as many tubes 11 as there are ducts in the bar 10, and as many openings 13 and 14 as there 110 are ducts in the different rows in the tracker bar.

It will be readily understood that either the member 4 or the bar 10 may be moved, the operation and result being the same 115 whether it be the chamber 4 or the bar 10 that is given the movement, such movement being dependent, of course, upon which of said members is fixed. If the member 4 is fixed, manipulation of the lever 17 will move 120 the bar 10 thereupon or with relation thereto. If the bar 10 is fixed, manipulation of the lever will reciprocate the chamber 4 upon or with relation to said bar 10.

In order to guide and limit the movement 125 of the parts 4 and 10 with relation to each other, I provide the member 10 with a vertical slot 28, in which works a stud or pin or projection or the like 29 extending from the chamber 4. This pin and slot serve also to 130

limit the movement of the one part with relation to the other and the length of the slot is such that when brought to its limit of movement in one direction or the other, the movable part will be in such position as to bring the ports 13 or 14 in such position as to communicate with their respective tubes 6 or 8. In order to hold the parts 4 and 10 in close frictional engagement with each other, I mount upon the stud or pin 29 a spring 30, as seen in Figs. 2, 3 and 4, which bears between its ends against the head 31 of the stud 29 and at its ends against the bar 10, it being understood that there are two of these guide slots and studs and springs, one near each end, so as to insure parallelism of movement of the parts. The frictional engagement is such as to insure practically an air-tight joint between the adjacent faces of the two parts, yet permit of sliding movement in order to shift their relative positions.

With the parts constructed and arranged substantially as hereinbefore described, the operation will be apparent. Briefly stated, it is as follows: As shown in Fig. 2, the parts are in position to adapt the player for playing eighty-eight note music. The ports 13 are in communication with the tubes 6 and the ports 14 are in communication with the bleeds 15, the bleeds 16 being shut off or closed. When in this position, communication is afforded between the tubes 6, the ducts 12 and through such ducts and the tubes 11 to the sound producing devices and also through such ducts, the ports 14 and bleeds 15 and tubes 5 to the action. When it is desired to adapt the player for use in connection with sixty-five note music, the lever 17 is actuated so as to shift the relative position of the parts 4 and 10, when the parts will be brought into the position in which they are seen in Fig. 3, the ports 14 being in communication with the tubes 8, the bleeds 15 being closed and the ports 13 in communication with the bleeds 16, so that communication is afforded between the ducts 12, ports 13, bleeds 16, chamber 4 and tubes 5 to the action, also through the tubes 11 to the sound producing devices.

Modifications in detail may be resorted to without departing from the spirit of the invention or sacrificing any of its advantages.

What is claimed as new is:

1. The combination with a tracker bar having two rows of ducts of different sizes, of a single chamber with bleeds of different sizes for relative coöperation with said different rows of ducts, connections between said tracker and bleeds, and a member frictionally held in contact with said chamber and having ports and constructed for coöperation with said bleeds.

2. The combination with a trackerbar having two rows of ducts of different sizes,

of two members one connected with the two rows of ducts of the trackerbar and one movable upon and relatively to the other, one of said members having ports and the other having bleed holes of different sizes 70 for relative coöperation with the ports in the other member.

3. The combination with a trackerbar having two rows of ducts of different sizes, of two members, one connected with the two 75 rows of ducts of the trackerbar and one movable upon and relatively to the other, one of said members having ports and the other having bleed holes of different sizes for coöperation with said ports, and means 80 for moving one of said members with relation to the other.

4. The combination with a trackerbar having two rows of ducts of different sizes, of two members one connected with the 85 trackerbar and one of which is movable upon and with relation to the other, one of said members constituting a single chamber with bleeds of different sizes and the other with ports for coöperation with said bleeds. 90

5. The combination with a trackerbar having two rows of ducts of different sizes, of two members one of which is in communication with the trackerbar and one of which is movable upon and with relation 95 to the other, one of said members having ports and the other constituting a single chamber with bleeds of different sizes for relative coöperation with the ducts of the trackerbar, and means for moving one of 100 said members to bring the bleeds of one size alternately into communication with the rows of ducts of the corresponding size.

6. A tracker bar having a plurality of 105 rows of ducts of different sizes, a valve member provided with a chamber, a second member, one of which members is movable upon and relatively to the other, one of said members having a duct and ports in communication with the ducts of the tracker bar, the other of said members having bleed holes of 110 different sizes relatively spaced whereby one is opened and the other closed as said movable member is shifted in its position to establish communication between one of the 115 ports and one of the ducts of the trackerbar.

7. A trackerbar having a plurality of 120 rows of ducts of different sizes, two juxtaposed members, one of which is movable upon the other, one of said members being in communication with the trackerbar and the other constituting a single chamber, said first-named member having ducts with a plurality of ports leading from each duct relatively spaced so that when one is in communication with one of said rows of ducts the other is out of communication with the other row, one of said members having sets of bleeds of different sizes relatively spaced 125 whereby when one bleed is in communica- 130

tion with one of said ports the other port is in communication with one of said ducts.

8. A trackerbar, two members one of which is movable with relation to the other, one having ports and the other constituting a single chamber and having a row of ducts, connections between said trackerbar and one of said members, and a plurality of bleed holes of different sizes for relative coöperation with said row of ducts, and means for moving one of said members to close one set of bleeds as the other set is opened.

9. A trackerbar, two members one of which is movable with relation to the other, one having ports and the other constituting a single chamber and having a row of ducts, connections between said trackerbar and one of said members, and a plurality of bleed holes of different sizes for relative coöperation with said rows of ducts, means for moving one of said members to close one set of bleeds as the other set is opened, and means for guiding and limiting the movement of the movable member.

10. A trackerbar, two members one of which is movable with relation to the other, one having ports and having a row of ducts and the other constituting a single chamber, connections between said trackerbar and one of said members, and a plurality of bleed holes of different sizes for relative coöperation with said rows of ducts, means for moving one of said members to close one set of bleeds as the other set is opened, means for guiding and limiting the movement of the movable member, and means for forcing it into air-tight engagement with the other member.

11. A trackerbar, two juxtaposed members one of which is movable with relation to the other, one having ports and a row of ducts and the other constituting a single chamber, connections between said trackerbar and one of said members, a plurality of bleed holes of different sizes for coöperation with said row of ducts, means for moving one of said members to close one set of said bleeds as the other set is opened, means for guiding and limiting the movement of the movable member, and means for forcing it into air-tight engagement with the other member, said last-named means coöperating with said guiding and limiting means.

12. The combination with a tracker bar having two rows of ducts of different sizes, of two juxtaposed members, one of which is movable with relation to the other, one of said members having ports and being capable of being connected with the rows of ducts of the tracker bar and the other of

said members constituting a chamber with bleeds of different sizes for coöperation with the ports in the other member.

13. A tracker bar having two rows of ducts of different sizes, a member connected with said rows of ducts and provided with a plurality of bleeds of different sizes, and ported means for closing one set of bleeds as the other set of bleeds is exposed.

14. A tracker bar having a plurality of rows of ducts of different sizes, coöoperating bleeds of different sizes, ported means affording communication between said bleeds and ducts and means for preventing leakage through one set of bleeds as communication with the player action of a mechanical instrument is established through the other set of bleeds.

15. A trackerbar having a plurality of rows of ducts of different sizes, a member connected therewith and having means for connection with a pneumatic action, and having bleeds of different sizes for relative coöperation with said rows of ducts, and movable ported means coöperating with said member for preventing leakage therein.

16. A trackerbar having a plurality of rows of ducts of different sizes, a member having a plurality of bleeds of different sizes adapted for connection with a player action, and a movable ported member for communication with the ducts of said tracker bar and for coöperation with said first-named member for cutting off communication between said bleeds and the player action.

17. A trackerbar having a plurality of rows of ducts of different sizes, a member having a plurality of bleeds adapted for communication with a player action, and coöperating ported means for communication with the ducts of the trackerbar for cutting off communication between said bleeds and the player action.

18. A trackerbar having a plurality of rows of ducts of different sizes, a member having a plurality of sets of bleeds adapted for communication with a player action, and movable ported means coöperating therewith and adapted for communication with the ducts of the trackerbar for cutting off communication between said bleeds and the player action.

Signed by me at Washington, D. C., this 7th day of May, 1910.
